UNITED STATES PATENT OFFICE.

J. PAUL BROWN, OF ATLANTA, GEORGIA.

UNION SUIT.

Application filed October 28, 1922. Serial No. 597,589.

To all whom it may concern:

Be it known that I, J. PAUL BROWN, a citizen of the United States, and a resident of Atlanta, in the county of Fulton and 5 State of Georgia, have invented certain new and useful Improvements in Union Suits, of which the following is a specification.

This invention relates to an improvement in union suits, and the object of the invention is to provide a union suit wherein the crotch seam and belt effect are entirely eliminated, the union suit being at the same time made up of three pieces and a pair of button strips whereby the construction of the suit 15 is simplified and the freedom and comfort afforded by it to the wearer are greatly enhanced.

Other objects and advantages of the invention reside in certain novel features of 20 the construction, combination and arrangement of parts which will be hereinafter more fully described and particularly pointed out in the appended claims, reference being had to the accompanying drawings forming part 25 of this specification, and in which:

Figure 1 is a perspective view, showing the preferred embodiment of the invention;

Figure 2 is a plan view of the three pieces which together with the button strips make 30 up the suit;

Figure 3 is a view in section, taken approximately on line 3—3 of Figure 1;

Figure 4 is a fragmentary perspective view of the lower part of the union suit, 35 showing the manner in which the parts are associated; and

Figure 5 is an enlarged section of the front part of the garment, taken on the same line as Figure 3 but showing the button 40 strips disassociated from each other.

Referring to the drawings it will be seen that the union suit is made up of three pieces, two combined front and side pieces, designated at 10 and 11, respectively, and a back 45 piece designated at 12, and a pair of button strips, designated at 13, and 14, respectively. The combined front and side pieces 10 and 11 are of identical construction and are formed with continuous straight vertical edges 15 and 16, respectively to which the button strips 13 and 14 are respectively attached. At the upper ends of the pieces 10 and 11 tabs 17 and 17^a and 18 and 18^a respectively are formed which coat with similar tabs 19 and 19^a and 20 and 20^a formed 50 on the back piece to complete the neck and

arm openings of the garment, the tabs 17 and 17^a and 18 and 18^a being secured to the tabs 19 and 19^a and 20 and 20^a, respectively. The edges 21 and 22 of the pieces 10 and 11, 60 respectively, are secured by lines of stitching to the edges 23 and 24, respectively of the back piece 12 to completely close the back of the garment.

At one side of the lower end of the pieces 10 and 11 pointed extensions 25 and 26 respectively are formed, these extensions being of simple construction and being in general of triangular shape. The lower end of the back piece 12 is also formed with extensions, 70 there being two extensions on the back piece, designated at 27 and 28, respectively, both of these extensions being similarly formed and presenting inclined edges 27^a and 28^a, 75 respectively.

In the form of garment illustrated the button strip 13 is stitched to the vertical edge 15 of the piece 10 and carries the buttons 30 while the button strip 14 is stitched to the vertical edge 16 from the neck opening down to the apex of the crotch. Below the crotch the button strip 14 is first stitched or otherwise secured to the inclined edge 27^a of the extension 27 of the back and beyond the extension 27 it is 80 stitched to the tab or extension 25 of the piece 10 so that this button strip 14 is organized with the three pieces of the garment. The other extension or tab 28 is secured by lines of stitching or the like to a 85 portion of the vertical edge 16 of the piece 11 lying just below the crotch and above the bottom of this piece 11, the portion of the vertical edge 16 which lies contiguous with the bottom being secured by lines of stitching or the like to the edge 26^a of the extension or tab 26. It is to be noted that the crotch is thus formed by the tabs or extensions 27 and 28 and the adjacent portion 90 of the back 12 and since these tabs are integral with the back the crotch thus formed is seamless. The front opening of the garment defined by the edges 15 and 16 of the pieces 10 and 11 or rather by the button strips 13 and 14 secured to these edges extends from the neck opening on a continuous straight line down to and through the crotch for it will be remembered that the button strip 14 is first secured to the edge 16 of the piece 11 for that portion of the 95 length of such edge that reaches from the neck opening to the apex of the crotch and

95

100

105

110

beyond the apex of the crotch it is secured first to the extension or tab 27 of the back which goes to make up the crotch and second to the extension 25 of the piece 10 thereby 5 extending through the crotch on a continuous straight line.

In this manner there is obtained a perfect fitting garment made up of three pieces and the button strips and entirely eliminating 10 crotch seams or belt effects around the waist line. This elimination of the crotch seam and the gathering in the belt line does away with any possibility of the suit pulling or binding in the crotch, the seat of the garment 15 tending rather to pull out instead of up in the crotch line in a sitting position as well as in other positions. Again without the necessity of manipulating fastening devices and flaps the garment may be 20 readily, conveniently and with comfort adjusted as required. Moreover these advantages are obtained while at the same time the process of manufacture is simplified and the quantity of material consumed 25 reduced.

I claim:

1. A union suit made up of three pieces and a pair of button strips, said three pieces including a back piece and two combined 30 front and side pieces, the combined front and side pieces having vertical edges and extensions at their lower ends at the opposite side from said vertical edges, said back piece having a pair of extensions at 35 its lower end and a button strip secured to the vertical edge of one of the combined front and side pieces from the neck opening to the apex of the crotch, said button strip being also secured to one of the extensions 40 of the back piece beyond the apex of the crotch and being further secured to the extension of the other combined front and

side piece beyond the point where it is secured to the extension of the back piece, the other extension of the back piece being 45 secured to the vertical edge of the first-mentioned front piece immediately below the apex of the crotch and the extension of said last mentioned front piece being secured to the lower portion of the vertical 50 edge of said front piece.

2. A union suit comprising a back piece and a pair of combined front and side pieces having edges stitched to the back piece, the combined front and back pieces 55 also having vertical edges adapted to be releasably secured together and defining a front opening extending on a continuous straight line from the neck opening through the crotch and through one of the leg sections, the back piece having a pair of integral extensions, one extension being stitched to a portion of the vertical edge of one of the combined front and side pieces, the other extension being releasably secured 60 into a portion of the vertical edge of the other combined front and side piece, the combined front and side pieces having a pair of integral extensions, one of the extensions of the combined front and side 65 pieces being united to a portion of the vertical edge of the combined front and side piece on which it is formed to provide one of the leg sections of the garment, the extension of the other combined front and side 70 piece being adapted to be releasably secured to the vertical edge of the combined front and side piece on which it is formed to complete the other leg section of the garment and to provide for the extension of the front 75 opening of the garment through one of the leg sections as well as through the crotch and through the body of the garment.

J. PAUL BROWN.
